UNITED STATES PATENT OFFICE.

ALEXANDER E. WEISTOCK AND HARRY DAHNE, OF BALTIMORE, MARYLAND.

PAPER BAG.

Application filed May 7, 1926. Serial No. 107,425.

This invention relates to bags of the type commonly used for carrying small parcels and it consists in the novel features and arrangement thereof as hereinafter described 5 and claimed.

A prime object of the invention is to provide in conjunction with a bag proper a single cord for supporting the same and which is so arranged with relation to the 10 side walls and the bottom wall of the bag as to effectually brace the bottom wall where the greatest strain occurs when the bag is filled.

Heretofore it has been the practice to 15 support the bag by different cord arrangements, as where an endless cord is threaded through openings in the sides of the bag proper and passed in parallel relation under the bottom. It has also been the practice 20 to provide a plurality of supporting cords with portions thereof passing under the bottom of the bag proper and interlaced with each other.

For obvious reasons it has been found 25 that it is desirable to provide a bag supporting means which does not penetrate through the bottom of the bag. It is also desirable to use but a single supporting cord and arrange the portions thereof so that the weight 30 of the objects within the bag pressing down upon the bag bottom particularly at the center of the bag bottom, will not have a tendency to break the bottom of the bag or cut through the bottom of the bag in consequence 35 of any sliding movement that the cord may have with respect to the body of the bag.

To this end, the invention resides in the construction, combination, and arrangement 40 of parts, elements and features, hereinafter more particularly pointed out.

In the accompanying drawing:

Figure 1 is a perspective view of the complete bag;

Figure 2 is a perspective view of the cord arrangement used in conjunction with the body of the bag.

The bag is formed from heavy paper and includes side walls 1 and a bottom wall 2. The bottom wall 2 is imperforate. Both of the side walls 1 of the bag are provided with upper spaced openings 3 and lower spaced openings 4. The respective openings 50 of the set of openings 3 and 4 are located

at equal distances beyond and at opposite 55 sides of the median vertical dimension of the side walls 1 of the bag.

A single cord 5 before being made endless by a single knot 6, is threaded inwardly 60 through the openings 3 and outwardly through the openings 4 in the lower portion of the sides of the bag. Portions 7 of the said cord extend diagonally from the openings 4 at one side of the bag around the edges and under the lower surface of the 65 bottom 2 of the bag and through the openings 4 at the opposite side walls 1 of the bag. Thus the portions 7 extend diagonally across the bottom of the bag and intersect or cross each other at the point 8 which 70 occurs at the center of the bottom wall 2 of the bag. Each portion 7 extends from the opening 4 at one side of the median vertical line of one side of the bag to the opening 4 lying at the opposite side of the 75 vertical median line of the opposite side wall 1 of the bag. Portions 9 of the cord extend above the upper edge of the bag to provide handles.

By this arrangement it will be seen that 80 the supporting cord reinforces and braces the bottom of the bag where the greatest strain occurs and the portions 7 may slip or slide without cutting or damaging the bottom of the bag. At the same time, the 85 sliding movement of the cord through the openings 3 and 4 will accommodate the cord to the folding of the bag, as in packing the bags, and in holding the bottom of the bag in its normal folded position when the bag 90 is not in use. It will also be seen that the paper bottom of the bag will not have to carry the load and be broken by the variety of objects carried in a bag of this kind in shopping use. In view of the fact that but 95 a single cord is used, a minimum amount of material is employed in the make up of the bag structure as an entirety and inasmuch as but a single knot is made in the cord, time is saved in assembling the parts. 100 At the same time a bag structure is provided which possesses maximum strength and durability. This is due to the reinforced crossing of the portions 7 under the center of the bottom of the bag giving the maximum support at the center of the bag bottom, where there is the greatest weight and strain brought by the contents of the bag.

2
Approximately at the point 8 where the portions 7 of the cord cross each other a ring 9 is provided and the said portions 7 are threaded through the said ring as best shown in Figure 1 of the drawing. Thus the portions 7 may have limited longitudinal sliding movement with relations to each other but the side ring will hold the point of intersection 8 at all times approximately 10 at the center of the bottom of the bag and therefore it will be impossible for the portions 7 to swing around the ends of the bottom 2 of the bag and become displaced with respect to each other and with relations to the bag bottom.

From the foregoing description of the construction of our improved device, it will be seen that we have provided a simple, inexpensive and efficient means for carrying 20 out the objects of the invention and while we have particularly described the elements best adapted to perform the functions set forth, it is obvious that various changes in form, proportion and in the minor details 25 of construction may be resorted to without departing from the spirit or sacrificing any of the principles of the invention.

Having thus described our invention what we claim is:

A paper bag having an imperforate bottom wall, the side walls of the bag having upper and lower openings located at equal distances beyond the median vertical dimension of the side walls and an endless cord threaded through the openings in the side walls of the bag and projecting above the edge of the bag to form handles, said endless cord being disposed exteriorly of the lower portion of the side walls of the bag and exteriorly of the bottom wall, said cord having portions extending diagonally from the lower openings in the opposite side walls of the bag directly and completely across the under surface of the bottom of the bag and around the edges thereof and 45 the portions of the cord at the same side of the bag converging toward each other from the openings toward the bottom of the bag and a ring surrounding the diagonally disposed portions of the cord. 50

In testimony whereof we affix our signatures.

ALEXANDER E. WEISTOCK.
HARRY DAHNE.
